(57) **CLAIM**

I claim the ornamental design for an electric contact, as shown and described.

DESCRIPTION

FIG. 1 is a front elevation view of an electric contact showing my new design;

FIG. 2 is a rear elevation view thereof;

FIG. 3 is a right side elevation view thereof;

FIG. 4 is a left side elevation view thereof;

FIG. 5 is a top plan view thereof; and,

FIG. 6 is a bottom plan view thereof.

The ornamental design which is claimed is shown in solid lines in the drawings. The broken lines in the figure drawing views are included for the purpose of illustrating environment and form no part of the claimed design.
